UNITED STATES PATENT OFFICE

2,523,387

TAPE TENSION CLAMP FOR SLIDE FASTENER MACHINES

Alfred G. Natzke, Lynbrook, N. Y., assignor to
Lamar Slide Fastener Corp., New York, N. Y.,
a corporation of New York

Application October 8, 1945, Serial No. 620,866

4 Claims. (Cl. 271—2.3)

1

This invention relates to machines for making slide fasteners and more particularly to the means provided in such machines for driving the flexible material to which the fastener elements are attached in the operation of the machines.

In the manufacture of slide fasteners, the fastener elements or scoops are clamped in succession upon a beaded tape or the like, which is fed to a machine wherein it is given an intermittent or step-by-step movement in predetermined time relation to the feeding of the scoops, these latter being either separately produced, hoppered and individually conveyed to the tape, or finished in the same machine wherein their clamping to the tape is effected according to various methods, for instance from interconnected series of embryo scoops. In all cases it is essential that the tape be properly tensioned and its movement accurately controlled in order to secure the exact spacing between successive scoops required for the smooth operation of the slide fastener, or to provide gaps of predetermined length between series of scoops defining fastener stringers and obtained through the continued movement of the tape while the feeding of the scoops thereto is interrupted.

A commonly used type of mechanism for driving the tape comprises a tape feed drum suitably rotated in synchronism with the scoop feeding and clamping means and usually having a knurled periphery for frictional engagement of the surface of the tape, and a tape holding and tensioning device associated with the drum which consists of a spring pressed shoe adapted to hold the tape against the drum periphery, whereby to insure constant driving engagement of the tape by the drum and maintain the tape sufficiently taut.

It is well known to those skilled in the art that such mechanisms are not entirely satisfactory and do not always insure such an accurate spacing of the scoops as might be desired, chiefly because the relatively high pressure applied by the stationary shoe on the tape and required to prevent sliding of the tape relative to the drum results, at a high speed of operation of the machine, in an objectionable friction and strain on the tape and often causes a slight pinching or folding of the tape, the cumulative effect whereof is sufficient to produce uneven advancement of the tape and spacing of the scoops.

It is therefore the primary object of the invention to provide a novel and improved tape tensioning and holding device associated with a tape driving drum which, while effective to hold the tape against the drum periphery and positively to prevent lost motion, thereby insuring uniform spacing of the scoops at any time, eliminates any objectionable friction on the tape and the shortcomings caused thereby.

Another object is to provide means, as aforesaid, which are of simple construction, reliable in operation, applicable to slide fastener machines employing the usual tape feed drum without changing the structure of such machines, and subject to a minimum of wear.

2

A further and more specific object is to provide a device for holding the tape against the driving drum wherein the usual friction shoe is dispensed with and the holding action is effected through pressure exerting means maintained in rolling engagement with the tape during the advancement of this latter.

These and other objects will become apparent in the following description of the invention illustrated in the drawings wherein:

Fig. 1 is a perspective view of a portion of a machine for making slide fasteners incorporating a device according to the invention.

Fig. 2 is an enlarged side elevation of the device of Fig. 1, shown in operative position.

Fig. 3 is a longitudinal section of the device shown in retracted or inoperative position.

Fig. 4 is a top plan view of the device, partly in horizontal section on line 4—4 of Fig. 2.

Referring now in detail to the drawings, 10 indicates a conventional tape feed drum fastened to a shaft suitably journaled in stationary element 11 or portion of the frame of the machine, the shaft being driven with a step by step motion in predetermined time relation to the scoop feeding and clamping means of the machine through suitable kinematic connections not shown. The periphery of the drum 10 is preferably knurled, as at 12, and the tape 13 is frictionally engaged by said knurled surface to be driven thereby.

30 A bracket 14, suitably fastened to the stationary element 11 aforesaid in proximity of the drum 10, slidably carries at its free end a shaft 15 which is radially aligned with the drum and has fast thereon, at its rear end, a collar 16 provided with radially extending grooves 17 best shown in Fig. 3. Freely mounted on the shaft 15 between the collar 16 and the free end of the bracket, is a further collar 18 carrying a lever 19 and provided with cam projections 20 profiled to fit the grooves 17 and normally received therein, the rotation of said collar 18 being effective to disengage the cams 20 from the grooves 17 and longitudinally to displace the shaft 15 in a rearward direction 45 for the purpose hereinafter set forth.

The forward end of the shaft 15 is provided with an integral fork 21 and a flange 22, a coil spring 23 being mounted on the shaft between said flange and the free end of the bracket 14 50 to urge the shaft 15 in a forward direction toward the drum 10. An elongated member or yoke 24 comprises parallel plates 25 that are centrally united by an integral portion of the member formed with a projecting tongue 26 (see Figs. 3 and 4) which is adapted to be received within the fork 21 and is mounted therein by means of a pin 27 so as to pivotally connect the member 24 to the shaft 15. The front portion of the plates 25 is centrally undercut to define an arcuate surface 28, the radius whereof is substantially equal to the radius of the drum 10.

Mounted between the plates 25 at their opposite ends, are two rollers 29 rotatably carried by pins 30 secured to the plates, the rollers prefer-

ably having a knurled peripheral surface as shown in Fig. 1, and projecting from the front of the plates. Said rollers are normally maintained in pressure exerting engagement with the tape on the drum by the spring 23 acting to urge the shaft 15 and associated elements toward the drum, the central portion of the member 24 being prevented from contacting the tape by the undercut portions 28.

As will be apparent, in the operation of the machine, the tape is therefore held against the periphery of the drum and thereby caused to move with the drum in the intermittent motion of this latter, while being maintained sufficiently taut in correct relation to other elements of the machine. The pressure is exerted by the rollers on the tape at considerably spaced points along the periphery of the drum and is sufficient positively to prevent any lost motion.

On the other hand, due to the fact that the pressure exerting rollers are obviously caused to rotate during the movement of the tape which they engage, this latter is not subject to any objectionable friction and any tendency of the tape to form folds is entirely eliminated. The pivotal connection of the roller-supporting member 24 with its carrying shaft 15 permits oscillation of the member and therefore insures constant engagement of the tape by both rollers irrespective of irregularities on the surface of the tape or the like, with the consequent even pressure on the tape and smooth action of the device.

To render the mechanism inoperative whenever desired for changing the tape or any other reason, it is manifestly sufficient manually to operate the lever 19 to displace the shaft 15 rearwardly as aforementioned, so as to withdraw the rollers from the drum and release the tape.

It will be understood that changes and modifications may be made in the structures described and illustrated in the drawings, without departing from the spirit of the invention or exceeding the scope of the claims.

I claim:

1. In a machine for making slide fasteners comprising a rotatable drum for feeding a tape for mounting fastener scoops, a bifurcated member slidably movable toward and away from said drum, a support member adjacent said drum and pivotally mounted on said movable member within the bifurcation thereof, a stop at the end of said movable member distant from said bifurcation thereof, a pair of spaced knurled rollers carried by said support member, adapted to engage the tape on the drum at spaced points, means for normally urging said movable member toward the drum to maintain said rollers in pressure-exerting engagement with the tape and the tape in engagement with the drum at the points of contact of the rollers, and means operable against said stop to longitudinally displace the same and to move the movable member and therefore the support member against said spring away from the drum to release the tape.

2. In a machine for making slide fasteners comprising a rotatable drum for feeding a tape for mounting fastener scoops, a bracket, a shaft slidably carried by said bracket, a bifurcation at one end of said shaft and a fixed collar at the other end thereof, an elongated member pivotally connected centrally thereof in the bifurcation of said shaft and extending adjacent the periphery of said drum, a pair of spaced rollers mounted at the opposite ends of said elongated member equidistant from the pivoted connection thereof,

spring means associated with the shaft and the bracket for urging the shaft toward the periphery of the drum to press said rollers into contact with a tape on said periphery and hold the tape in driven engagement with the drum, and cam means rotatably actuatable for displacing the collar, and therefore, the shaft away from the drum to withdraw the rollers from the tape.

3. In a machine for making slide fasteners comprising a rotatable drum for feeding a tape for mounting fastener scoops, a bracket, a shaft slidably carried by said bracket, an elongated member pivotally connected centrally thereof to one end of said shaft and extending adjacent the periphery of said drum, a pair of spaced rollers mounted at the opposite ends of said elongated member, spring means associated with the shaft and the bracket for urging the shaft toward the periphery of the drum to press said rollers into contact with a tape on said periphery and hold the tape in driven engagement with the drum, and manually operable cam means acting longitudinally against said shaft for displacing the shaft away from the drum to withdraw the rollers from the tape.

4. In a machine for making slide fasteners comprising a rotatable drum for feeding a tape for mounting fastener scoops, a bracket, a shaft slidably carried by said bracket, an elongated member pivotally connected centrally thereof to one end of said shaft and extending adjacent the periphery of said drum, a pair of spaced rollers mounted at the opposite ends of said elongated member, spring means associated with the shaft and the bracket for urging the shaft toward the periphery of the drum to press said rollers into contact with a tape on said periphery and hold the tape in driven engagement with the drum, a collar rigidly carried by said shaft near the other end thereof, a sleeve member rotatable with respect to said shaft and interposed between said collar and said bracket, cooperating cam and cam groove means provided in the adjacent portions of said collar and sleeve member, whereby when said cam and cam groove means are in engagement said spring means are allowed to maintain the shaft in a position wherein said rollers are in pressure engagement with the tape, and means for manually rotating said sleeve member to bring said cam and cam groove means out of engagement with one another and thereby to displace the shaft away from the drum to withdraw the rollers from the tape.
